UNITED STATES PATENT OFFICE

ERWIN RICHARD LAUBER, OF EMMISHOFEN, SWITZERLAND

FURNACE FOR THE PRODUCTION OF ALUMINUM

Application filed June 28, 1926, Serial No. 119,159, and in Germany July 30, 1925.

For the electrolytic separation of aluminum furnaces have hitherto chiefly been employed in which the supply of current to the actual liquid aluminum cathode is effected 5 through an auxiliary cathode which serves at the same time as the furnace bottom. This auxiliary cathode consists of iron or copper covered with a compressed carbon mass, which on the one hand forms the medium of 10 current supply between the iron or copper auxiliary cathode and the liquid cathode, and on the other hand protects this metallic auxiliary cathode from attack by the liquid aluminum. Such furnace bottoms have, in 15 new furnaces, a transition resistance in favourable cases of 0.4 volt which gradually rises to from 1 to 1.5 volts. The actual aluminum cathode is consequently heated according to the resistance of the furnace bottom, 20 which is very undesirable, but up to the present has been found unavoidable.

Of the electrical energy introduced into the aluminum furnace about 30 per cent on an average is used for the production of aluminum, while the rest is radiated in the form 25 of heat. Part of the electrical energy radiated in the form of heat could be saved, if the furnace, and more particularly the furnace bottom, could be thermally insulated to prevent losses of heat. In the case of the furnace bottoms hitherto employed such thermal insulation is impossible. The thermally insulated carbon bottom could only give up to 30 the aluminum cathode the heat produced in consequence of its resistance, which, in consequence of the overheating of the aluminum, would lead to poor current utilization and would quickly destroy the furnace bottom. On this account the metallic auxiliary cathode, and with it the carbon bottom, have hitherto been suitably cooled by means of air.

According to the present invention the current is supplied to the liquid aluminum cathode by means of graphite blocks in any suitable and convenient manner. It is sufficient to suspend one or more blocks of graphite in the liquid bath from above until they touch the liquid aluminum cathode. The graphite 45 block or blocks take over the conducting of

the current and do it in such an advantageous manner that the resistance of the graphite current supply, including the resistance of the liquid aluminum cathode, moves constantly in the order of magnitude of 0.1 volt. The 55 graphitic current supply to the liquid aluminum cathode may also be effected in any convenient and suitable manner by embedding the graphite blocks in the sides or bottom of the furnace, provided care is taken that the 60 graphitic surface always remains in direct contact with the aluminum cathode.

Certain ways in which it is possible to supply the current to the aluminum cathode are illustrated in the accompanying drawings. 65 In these drawings the letter *a* indicates the thermal insulation, *b* the furnace bottom made of mineral substances, *c* the graphite mass, *d* and *d'* the current supply, *e* the liquid molten aluminum, *f* the molten cryolite, *g* the electrodes forming the anode and *k* a compressed carbon mass.

Since, in graphitic current supply, which has practically no resistance, even when supplying the current from the bottom of the furnace, no heating action takes place, the metallic auxiliary cathode and also the layer of compressed carbon hitherto utilized between the metallic auxiliary cathode and the liquid metal, are both superfluous.

According to the present invention therefore the bottom of the furnace may be made of mineral substances which are not attacked by liquid aluminum. Blocks or rammed masses of alumina, corundum, magnesium oxide and the like are particularly suitable for making the furnace bottoms. The liquid aluminum cathode which separates the melt of cryolite from the mineral bottom, protects 80 the bottom from attack by the melt.

A coating of compressed carbon as a protective layer over a less suitable stone bottom, such as chamotte for example, does not in any way alter the invention, as this rammed or compressed material is no longer being considered for the supplying of current and consequently is not heated by the passage of current.

As contrasted with the furnaces hitherto

known the new furnace permits of complete insulation of the furnace bottom.

The furnace is also suitable for the electrolytic production of other metals, such as calcium, magnesium or the like.

5 What I claim is:—

1. For the production of metallic aluminum from molten aluminous materials by electrolysis, an electric furnace having a furnace bottom consisting of mineral substances that are not attacked by molten aluminum, thermal insulating means for said furnace bottom, a cathode of molten aluminum on the said bottom, an anode in said furnace 10 above said cathode, blocks of graphite in direct contact with the molten aluminum cathode, and means for supplying electric current to the anode and to said blocks of graphite.
- 15 2. For the production of metallic aluminum from molten aluminous materials by electrolysis, an electric furnace having a furnace bottom consisting partly of mineral substances that are not attacked by molten aluminum, thermal insulating means for said furnace bottom, a cathode of molten aluminum on the said bottom, an anode in said furnace 20 above said cathode, blocks of graphite in direct contact with the molten aluminum cathode, and means for supplying electric current to the anode and to the said blocks of graphite.
- 25 3. For the production of metallic aluminum from molten aluminous materials by electrolysis, an electric furnace having a furnace bottom consisting of mineral substances that are not attacked by molten aluminum, thermal insulating means for said furnace bottom, a cathode of molten aluminum on the said bottom, an anode in said furnace 30 above said cathode, blocks of graphite, not forming part of the furnace bottom, in direct contact with the molten aluminum cathode, means for supplying electric current to the anode and to the said blocks of graphite, and means for thermally insulating the furnace.

45 In testimony whereof I have affixed my signature.

50 ERWIN RICHARD LAUBER.
